MULTI-PIN CONNECTOR WITH PROTECTIVE SHIELD

John P. Kostich, deceased, late of Ontario, Calif., by
Helen S. Kostich, administratrix, Ontario, Calif.,
assignor to Northrop Corporation, Beverly Hills, Calif.,
a corporation of California

Filed May 14, 1962, Ser. No. 194,734

1 Claim. (Cl. 339—42)

The present invention relates to electrical connectors and more particularly to a multi-pin connector having a depressible protective contact pin enclosure or shield.

Heretofore, multiple-pin male electrical connectors, having numerous small, relatively fragile, electrical contact pins, were subject to physical damage by accidental or rough treatment. In addition, exposure of these contact pins, such as during maintenance and repair under operating conditions, created an electrical shock hazard to personnel and liability of accidental short circuit of two or more of the pins together, particularly in large systems interconnected by cabling in which all relatively high voltages cannot be confined to terminating at female receptacles only, wherever a cable connection is disconnected or unplugged. Previous means for preventing pin damage and shock hazards have been cumbersome and ineffective.

It is an object of this invention to provide a multi-pin electrical connector with means preventing damage to the pins, accidental short circuiting thereof, and shock to handling personnel when the connector is separated from its mating receptacle.

A further object of the present invention is to provide means automatically covering and protecting the pins of a multi-pin male connector whenever it is unplugged.

It is another object of this invention to provide a multi-pin male connector structure having a simple, economical and reliable shield movable between two positions where the pins are exposed and enclosed, respectively.

A still further object of this invention is to provide simple means for removing individual contact pins of the plug.

Briefly, the invention comprises a male connector having a recess in the pin end, and an elastically-urged shield having apertures therethrough for the connector pins, the shield being depressible into the recess when inserted into a corresponding mating receptacle. Additionally, the connector comprises self-locking contact pins adapted to be secured to external wire leads, and access means in the sides of the connector for unlocking, removal and replacement of individual pins without the use of special tools. Captive screw means are provided to secure the connector to its associated receptacle.

In the accompanying drawings,

FIGURE 1 is a composite side elevation and sectional view of a connector assembly, showing a pin enclosure shield in extended position.

FIGURE 2 is partial sectional view similar to FIGURE 1, showing the pin shield in retracted position.

FIGURE 3 is a plan view of the connector assembly, showing the pin end thereof, as indicated by the line 3—3 in FIGURE 1.

FIGURE 4 is a perspective view of a second embodiment of the present invention, showing a different preferred form of retractable pin shield in the extended position.

FIGURE 5 is a cross section of the latter assembly, taken as indicated by the line 5—5 in FIGURE 4, showing the contact pins and their locking means.

FIGURE 6 is a bottom plan view of the assembly, viewed as indicated by the line 6—6 in FIGURE 4.

2

FIGURE 7 is a longitudinal section view of the connector of FIGURE 4, taken at several levels thereof as indicated by the broken line 7—7 in FIGURE 6, showing the various internal parts and construction.

5 FIGURE 8 is a side elevation view of the connector with the cover removed and the pin shield in retracted position, showing the pin unlocking access openings.

FIGURE 9 is a side elevation view of a further embodiment of connector assembly, showing a right-angled 10 adapter thereon.

Referring first to FIGURE 1 for a detailed description of the present invention, an electrical cable 1 is secured in a connector cover 2 by an integral clamp 4. A connector base 5 made of insulating material and having 15 threaded inserts 6 is fastened to the cover 2 by screws 7. The base 5 is provided with a shield recess 9, contact pins 10 supported in the base, and a pair of captive guide and shield retaining means such as the one shown at 11. Contact pins 10 extend internally to an open space 12 20 for respective fastening to individual wires 13 in the cable 1.

A depressible and protective shield 14, also of insulating material, has pin apertures 15 and guide apertures 16 to permit free sliding movement over the pins 10 and 25 retaining means 11. A preloaded spring 17 installed on each guide means bears against the shield 14 to push the latter outwardly when the connector is disengaged from a corresponding mating receptacle (not shown).

Captive fasteners 19 are to secure the connector assembly to the mating receptacle when installed.

When the connector is disengaged, the shield 14 springs out to the position shown in FIGURE 1, where the contact pins 10 are enclosed. When connected to its mating receptacle, the shield 14 is forced into the recess 9 as 35 shown in FIGURE 2, and the exposed pins 10 are operatively connected in the receptacle.

FIGURES 4 through 8 illustrate a preferred embodiment differing somewhat from that already described. In FIGURES 4, 5, and 7, the shield 14a is shown extended, while in FIGURE 8 the shield is shown retracted against the pressure of the internal springs. Corresponding parts are given the same reference numbers as in FIGURES 1-3 with the suffix "a" added. The cover 2a is a sheet metal part fastened to the base 5a by a 40 screw 7a near each end of the cover 2a, as best shown in FIGURE 7. The captive fasteners 19a which secure the connector assembly to its receptacle (not shown) have a lock ring 20 fitting into a groove inside the cover 2a so that they will not become separated when the 50 cover is removed.

The contact pins 10a each comprise a flat strip of metal, such as a copper alloy, doubled back on itself and ending in a curved out barb 21 which locks against the inner upper side of a pin removal aperture 22 in the side of the base 5a. A shoulder 24 on each pin 10a limits the downward location of the pin when inserted. The wires 12a are preferably crimped in the upper receiving portion 25 of the pin 10a and may be soldered if desired.

60 By removing the cover 2a, the removal apertures 22 are reached, whereby individual leads can easily be unlocked and removed, as shown in FIGURE 8, by pressing inwardly on the barb 21 with any convenient instrument. This is made possible with a wire in either of the two rows, by providing the removal apertures on both sides 65 of the base 5a, and inserting the pin with the barb thereof facing outwardly. It will be noted that the "back" side of each pin 10a is straight and the inner vertical extent 26 of the base 5a to the rear of each pin is 70 smoothly continuous, whereby if a pin is inadvertently inserted backward, it will not lock to make it non-removable.

The shield 14a is slidably held in place by a retaining screw 27 near each end, and a pair of small compression springs 29 seat in base and shield sockets 30 and 31 respectively for automatically forcing the shield outwardly.

In the embodiment of FIGURES 4-8, a clamp means 32 is provided in the top of the cover 2a for leading out the wires 12a. FIGURE 9 shows an alternate form of the invention wherein a right-angled adapter 34 is provided at the top of the cover 2b. A wire entrance 35 in one edge of the adapter 34 guides the wires 12b out at the side for applications where adjacent plug locations are encountered.

Insertion of this connector device into a mating receptacle forces the protective shield back into the connector base, thus permitting the male and female connectors to make electrical contact. As the connector is disengaged from the receptacle, the pin shield automatically extends to provide an enclosure for protecting the pins from physical damage. In addition, the shield provides insulation to prevent accidental short circuiting of the pins as well as protecting operating personnel from possible electrical shock.

By making the shield a free sliding fit on all four sides with the base recess, a jam-proof, reliable, easy-working operation is obtained. The pins may be permanently molded in the base or individually removable. Compactness is achieved by locating the shield retaining screws within the pin envelope area and by placing the screws 7a and captive fasteners 19a as nearly side by side as possible (FIGURE 6). An indexing alignment feature is provided by chamfers 36 on only one side of the shield 14a, so that when the receptacle is correspondingly shaped, the connector cannot be reversed from its proper inserted position.

While in order to comply with the statute, the invention has been described in language more or less specific as to structural features, it is to be understood that the invention is not limited to the specific features shown, but that the method and means herein disclosed comprise several forms of putting the invention into effect, and the invention is therefore claimed in any of its forms or modifications within the legitimate and valid scope of the appended claim.

What is claimed is:

An electrical connector comprising a base, means de-

fining a recess in the external connection end of said base, a plurality of contact pins mounted in said base and extending outwardly beyond the end of said base, a shield member comprising a block having apertures therethrough corresponding to the locations of said pins, said shield being slidably mounted over said pins and fitting into said recess, elastic means between said base and said shield normally urging said shield outwardly to cover the extent of said pins, shield retaining means limiting the extended position of said shield, said recess being deep enough to allow operative engagement of said pins in a corresponding receptacle when connected therewith, a cover over the end of said base opposite the connection end, attachment means between said cover and said base, fastening apertures through said base at opposite sides thereof, fastening means in said apertures adapted to engage a structure to which said connector connects, said pins being in two rows, each said pin including stop means thereon limiting the inserted position thereof in said base, a resilient barb on the side of each pin normally spreading outwardly therefrom, a barb retaining inner wall in said base at each pin, and a side opening in said base at each pin giving access to said barb at said retaining wall for pressure on said barb to release said pin, said side openings being normally covered by said cover, and said pins being thus removable from the wire connection end of said connector.
